(57) **CLAIM**

The ornamental design for a trim component, as shown and described.

DESCRIPTION

FIG. 1 is a cross-sectional view of a first embodiment of a trim component, taken along line 1-1 in FIG. 2.

FIG. 2 is a side elevation view of the trim component of FIG. 1, which indicates a cross-section line 1-1.

FIG. 3 is a perspective view of the trim component of FIG. 1.

FIG. 4 is a perspective view of the trim component of FIG. 1.

FIG. 5 is a perspective of the trim component of FIG. 1.

FIG. 6 is a front elevation view of the trim component of FIG. 1.

FIG. 7 is a rear elevation view of the trim component of FIG. 1.

FIG. 8 is a cross-sectional view of a second embodiment of a trim component, taken along line 8-8 in FIG. 9.

FIG. 9 is a side elevation view of the trim component of FIG. 8, which indicates a cross-section line 8-8.

FIG. 10 is a perspective view of the trim component of FIG. 8.

FIG. 11 is a perspective view of the trim component of FIG. 8.

FIG. 12 is a perspective of the trim component of FIG. 8.

FIG. 13 is a front elevation view of the trim component of FIG. 8; and,

FIG. 14 is a rear elevation view of the trim component of FIG. 8.

The trim component is shown with a symbolic break in its length. The appearance of any portion of the trim component between the break lines forms no part of the claimed design. The broken lines in the drawings illustrate portions of the trim component that form no part of the claimed design.
